Shuttleworth & Ingersoll, PLC(57) CLAIM

The ornamental design for a storage cabinet, cart and chest, as shown and described.

DESCRIPTION

FIG. 1 is a perspective view of the storage cabinet, cart and chest showing my new design;

FIG. 2 is a front elevational view thereof;

FIG. 3 is a rear elevational view thereof;

FIG. 4 is a top plan view of the cabinet thereof; shown without the chest for completeness of illustration;

FIG. 5 is a bottom plan view thereof;

FIG. 6 is a right side elevational view thereof; and,

FIG. 7 is a right side elevational view thereof.

The broken lines shown in the drawings are for illustrative purposes only and form no part of the claimed design.
